ELECTRONIC SCANNING DEVICE FOR
TELEVISIONAndré Paul Paumier, Seceaux, France; vested in
the Alien Property CustodianApplication May 6, 1939, Serial No. 272,073
In France May 12, 1938

9 Claims. (Cl. 250—153)

It is known that the electronic scanning devices used for television by the name of "iconoscopes" generally have the defect of superposing on the picture modulation a parasitic modulation which causes the appearance of dark patches of more or less large area, called "marks." It appears to be acknowledged that these marks originate from secondary emission phenomena which occur in the "iconoscope," and that spatial distribution is connected with the manner in which the photo-electric mosaic plate is scanned with the cathode-ray scanning beam. Various methods have hitherto been proposed for compensating or "correcting" the marks in question, starting in general from a development of the "parasitic modulation" function in MacLaurin's progression which is stopped at its second or third term, and experimentally adjusting the numerical values and the phases of the t and t^2 terms, t representing the time, which are produced by appropriate generators.

This correction requires accurate adjustments which have to be re-adjusted from time to time, and only gives partially satisfactory results. The present invention relates to a method of correction which is quite different and the success of which has been proved by experience. It essentially consists in the use of a magnetic correcting field of relatively small amplitude, the action of which may be assumed to be exerted on the very soft secondary (parasitic) electrons which cause the marks as has been suggested. The direction of said magnetic field has to be substantially parallel with the cathode-ray beam of the "iconoscope" and inclined relatively to the surface of the scanning screen.

These conditions are set forth in detail in the ensuing description taken with reference to the accompanying drawing which shows by way of example an embodiment of a device according to the invention.

In the drawing, a scanning tube called "iconoscope" is shown. Said tube 1, the actual construction of which is not a part of the invention, essentially comprises a screen 2 and a cathode-ray oscilloscope 3. The screen 2 is formed by a metal collecting plate which is separated from a mosaic of photo-electric elements by an insulating plate. On said screen is projected the image to be scanned 4 by means of an optical system 5. The oscilloscope essentially comprises a cathode 6, a grid 7, a first anode 8 and a second anode 9, and also means 10 for causing the cathode-ray beam to deviate in two directions at right angles, so as to scan the screen 2. It is of course

understood that this description of the tube 1 is only given by way of example in order to illustrate the present invention and as a reference to the arrangement of the tubes called "iconoscopes" to which the present invention relates.

Experience has shown that by modifying a continuous magnetic field, for example by means of a coil surrounding the head of the iconoscope, it was possible to compensate more or less the marks of the picture of which mention was made above. The compensating action is complete for a direction of the field that makes an angle of about 45° with the plane of the mosaic plate, or approximately parallel with the axis of the cathode-ray oscilloscope; this compensation becomes zero for a field parallel with the plane of the mosaic plate. Finally it is only exerted on values of the brilliance of the picture which are not too high; in fact, when said brilliance increases, the intensity of the compensating field has to be increased, and this quickly leads to values which interfere with the scanning of the mosaic plate.

By way of a non-limitative example, for an "iconoscope" wherein the accelerating voltage of 25 the scanning beam was of the order of 1,000 v. and for a picture illumination of between 15 and 150 luxes, a compensating field of the order of 1 gauss proved satisfactory. Said field may be created by a coil 11 which is suitably arranged about the iconoscope and is supplied by a device 12 which supplies it with the necessary current.

Satisfactory results are also obtained with an alternating magnetic field of appropriate form and frequency, or with a field which is a discontinuous function of the time, for example which is of suitable intensity at certain instants or during certain very short intervals, and is zero outside said intervals, the frequency of the field being in this case preferably connected to the periodicity of the scanning, for example by controlling the device 12 by means of the same source of frequency which control the scanning device 10.

What I claim is:

1. A television transmitting tube comprising a mosaic screen formed by a conducting collecting surface, a mosaic of photo-electric elements, an insulating plate separating the latter from said surface, an electron gun, and deflecting means 50 for scanning said screen by the electron beam, means for creating inside the transmitting tube a magnetic field of small intensity relatively to the other fields existing in the tube, the direction of which is substantially parallel with the electron beam and is inclined relatively to said screen,

whereby parasitic modulation of the image projected on said mosaic screen is prevented.

2. A television transmitting tube comprising a mosaic screen formed by a conducting collecting surface, a mosaic of photo-electric elements, an insulating plate separating the latter from said surface, an electron gun, and deflecting means for scanning said screen by the electron beam, a coil surrounding said tube, the axis of said coil being substantially parallel with the electron beam of the tube and inclined relatively to said screen, and means for sending an electric current through said coil, whereby a magnetic field is created inside the tube which prevents parasitic modulation of the image projected on said screen.

3. A television transmitting tube comprising a neck portion, an electron gun inside said neck portion, a bulbous part adjacent to said neck portion, a mosaic screen being formed by a conducting collecting surface, a mosaic of photo-electric elements, an insulating plate separating the latter from said surface, and deflecting means for scanning said screen by the electron beam, a coil surrounding said bulbous part in the neighborhood of the screen, the axis of said coil being substantially parallel with the axis of the tube and inclined relatively to said screen, and means for sending an electric current through said coil, whereby a magnetic field directed to said screen is created inside the tube, which field prevents parasitic modulation of the image projected on said screen.

4. A television transmitting tube comprising a mosaic screen formed by a conducting collecting surface, a mosaic of photo-electric elements, an insulating plate separating the latter from said surface, an electron gun, and deflecting means for scanning said screen by the electron beam, means for creating inside the transmitting tube a continuous magnetic field of small intensity relatively to the other fields existing in the tube, the direction of which is substantially parallel with the electron beam and is inclined relatively to said screen, whereby parasitic modulation of the image projected on said mosaic screen is prevented.

5. A television transmitting tube comprising a mosaic screen formed by a conducting collecting surface, a mosaic of photo-electric elements, an insulating plate separating the latter from said surface, an electron gun, and deflecting means for scanning said screen by the electron beam, means for creating inside the transmitting tube an alternating magnetic field of small intensity relatively to the other fields existing in the tube, the direction of which is substantially parallel with the electron beam and is inclined relatively to said screen, whereby parasitic modulation of

the image projected on said mosaic screen is prevented.

6. A television transmitting tube comprising a mosaic screen formed by a conducting collecting surface, a mosaic of photo-electric elements, an insulating plate separating the latter from said surface, an electron gun, and deflecting means for scanning said screen by the electron beam, means for creating inside the transmitting tube a discontinuous magnetic field of small intensity relatively to the other fields existing in the tube, the direction of which is substantially parallel with the electron beam and is inclined relatively to said screen, whereby parasitic modulation of the image projected on said mosaic screen is prevented.

7. A television transmitting tube comprising a mosaic screen formed by a conducting collecting surface, a mosaic of photo-electric elements, an insulating plate separating the latter from said surface, an electron gun, and deflecting means for scanning said screen by the electron beam, a coil surrounding said tube, the axis of said coil being substantially parallel with the electron beam of the tube and inclined relatively to said screen, and means for sending a continuous electric current through said coil, whereby a magnetic field is created inside the tube which prevents parasitic modulation of the image projected on said screen.

8. A television transmitting tube comprising a mosaic screen formed by a conducting collecting surface, a mosaic of photo-electric elements, an insulating plate separating the latter from said surface, an electron gun, and deflecting means for scanning said screen by the electron beam, a coil surrounding said tube, the axis of said coil being substantially parallel with the electron beam of the tube and inclined relatively to said screen, and means for sending an alternating electric current through said coil, whereby a magnetic field is created inside the tube which prevents parasitic modulation of the image projected on said screen.

9. A television transmitting tube comprising a mosaic screen formed by a conducting collecting surface, a mosaic of photo-electric elements, an insulating plate separating the latter from said surface, an electron gun, and deflecting means for scanning said screen by the electron beam, a coil surrounding said tube, the axis of said coil being substantially parallel with the electron beam of the tube and inclined relatively to said screen, and means for sending a discontinuous electric current through said coil, whereby a magnetic field is created inside the tube which prevents parasitic modulation of the image projected on said screen.
